UNITED STATES PATENT OFFICE.

GORTON W. NICHOLS, OF CHICAGO, ILLINOIS.

IMPROVEMENT IN APPARATUS FOR EXTINGUISHING FIRES.

Specification forming part of Letters Patent No. 119,638, dated October 3, 1871.

To all whom it may concern:

Be it known that I, GORTON W. NICHOLS, of Chicago, in the county of Cook and the State of Illinois, have invented an Improved Apparatus for Extinguishing Fires; and do hereby declare that the following is a full and exact description thereof, reference being had to the accompanying drawing making part of this specification—

Figure 1 being a vertical section of the extinguisher; Fig. 2, external view of same.

Like letters designate corresponding parts in both figures.

In this extinguisher carbonic-acid gas is generated and projected upon the fire by the use and combined arrangement of the following principal parts and chemicals, as specified.

A strong metallic reservoir, A, provided with two cocks, B and F, is filled nearly full with a solution of carbonate of soda in water, to which is then added a proper proportion of sulphuric acid. Instantaneous generation of carbonic-acid gas follows, developing pressure sufficient to cast an elevated jet. The special manner in which the solution of acid is brought in contact inside the vessel A is by means of a large funnel-mouthed cock or faucet, B, firmly united to the reservoir A, and provided with an air-vent, D. The cock B being thrown open the carbonate of soda in powder is first introduced through it to the inside of the reservoir A, being poured or shaken out of an envelope or cartridge. Water in sufficient quantity is then also introduced through the cock B, which may be used to its full capacity as the air within the reservoir A escapes at the vent D, which opens and closes in common with the main passage through B. A bottle less in size than the orifice through B, filled with acid, after being first uncorked, is next dropped into the reservoir A through B, which is instantly closed, and the charging is complete. A short hose, with suitable nozzle, is attached to the cock F, through which the contents of A may be ejected. As the pressure in the reservoir A necessarily decreases as the contents are ejected at F provision is made, and the charging-cock B is used as an exhaust to instantly furnish adequate vent for the weaker portion of the charge, which, escaping at once, leaves the extinguisher empty and ready to be recharged, which in case of fire at an elevation is important, as pressure adequate must be maintained. This feature also makes

this extinguisher practicable for other than incipient conflagrations, rendering it capable of such rapid recharging that its effect in subduing fire is practically continuous. The acid never being introduced into the reservoir until the instant the machine is required to act, the charger remains always fresh and of the same generating power. Duplicate bottles of acid and packages of soda, prepared ready for use, are kept always convenient in a receptacle attached to some part of reservoir A, one form of which is shown at E. When the proper proportions of chemicals are brought in contact in a closed vessel of the proper capacity the carbonic-acid gas evolved produces a pressure of nearly one hundred pounds to the square inch, steam-gauge, capable, through the discharging nozzle commonly employed, of casting a jet forty or fifty feet perpendicular height. This pressure commences immediately to expand itself and to decrease, so that in from sixty to ninety seconds the height to which the jet is thrown is reduced fully one-half, and in a few seconds more so greatly as to be no further available. As extinguishers have been heretofore constructed, several minutes more must elapse for this unavailable remainder of the charge to expend itself before the head can be removed with safety and a new charge introduced. This last, also, by these old methods consumes too much time—so much, indeed, that extinguishers as now constructed are seldom or never recharged for use upon the same occasion. Fires which cannot be subdued in from one and a half to two minutes are given over to burn out or make work for the department. With my improvement, however, when the pressure has decreased so that the jet is no longer efficient, by a single movement of the hand the cock may be thrown open and the whole of the remaining portion of the gas instantly let escape. By this means from one-half ($\frac{1}{2}$) to two-thirds ($\frac{2}{3}$) of the water will be saved and retained inside the reservoir, to which may in a few seconds be added fresh materials and a pressure again produced of one hundred pounds to the square inch, and so on *ad libitum*.

It must be kept in view that the method of charging my extinguisher is unlike that of Mullanly's or any other heretofore constructed. By all previous methods the chemicals must be with great care arranged inside the reservoir and kept separate until after the secure closing of the same

before they can with safety be brought in contact. By my improvement the means of closing the reservoir is so simplified that the chemicals are safely brought in contact before the reservoir is closed, only a portion of a second being required to shut the cock.

In the light of the foregoing the advantages and novelty of my method of construction must be at once apparent. Instead of a leaky, cumbersome head piece, with its bolts and nuts, or Mulhall's impractical screw-plug, neither of which can serve the end I propose, I use a simple cock or faucet, opening or closing by a single motion of the hand. In connection with this, also, is the air-vent, which economizes time when water is being introduced. This simple form of constructing extinguishers also reduces their cost, and the charges, being carried in a receptacle attached to the machine, are always at hand.

I am aware that previous to the date of my invention, chemicals, either in liquid or in powder, have been so arranged that they might be brought in contact inside of a previously-closed vessel, so as to produce carbonic-acid gas; but as this method is not new I lay no claim, broadly, to its employment. I am also aware that water charged with carbonic-acid gas has been previously used

as a medium for extinguishing fires; but this being an invention of old date and in common use, I make no claim, broadly, to its employment.

What I claim as my invention, and desire to secure by Letters Patent, is—

1. The exhaust and charging cock B or equivalent, operating as and for the purpose specified.
2. The employment of a cock or equivalent, other than that to which the hose is attached, as a vent by which the contents of fire-extinguishers may be drawn off, as specified, for the purpose as set forth.
3. An air-vent, opening and closing simultaneously with and by the same means as the main passage to the reservoir, as set forth.
4. Attaching to fire-extinguishers a receptacle for holding charges, substantially as specified.
5. The combination of these several parts, as specified, for the purpose set forth.

In witness that the above is a true specification of my improved fire-extinguisher I have hereunto set my hand and seal this 9th day of March, 1871.

GORTON W. NICHOLS. [L. S.]
